RECEPTACLE FOR INFLAMMABLE FLUIDS

Edwin L. Nute, Wakefield, and Edward A. Willey,
Malden, Mass., assignors to Converse Rubber
Company, Malden, Mass., a corporation of
Massachusetts

Application December 24, 1941, Serial No. 424,376

5 Claims. (Cl. 220—89)

This invention relates to receptacle for volatile and inflammable fluids or semi-liquid materials and relates more particularly to a receptacle and to a support or holder therefor having associated therewith means operative to smother and extinguish the flames if the contents of the receptacle should be ignited.

In certain industries, for instance in the manufacture of rubber footwear, it is substantially necessary to keep small quantities of highly inflammable substances, for example naphtha in open vessels, usually metal pans, for current use during the manufacturing process. Obviously such open receptacles of fluid constitute a very serious fire hazard, for although any individual receptacle may be of relatively small capacity, the accidental ignition of its contents may be sufficient to start a fire of very serious proportions.

While the workers are usually instructed to empty such receptacles at the close of the day and to keep them covered when not in active use, such instructions are not always obeyed and even if they are, this would not be sufficient completely to avoid the danger of fire occurring during the normal performance of the manufacturing operation.

The principal object of the present invention is to provide a receptacle and holder (designed for such uses as above described) having provision for automatically extinguishing the blaze if the contents of the receptacle should be ignited. A further object is to provide a cover so designed and arranged as to close and thus cut off free access of air from the interior of the receptacle in the event of fire. A further object is to provide a receptacle-cover so mounted as to permit it to move toward and from closed position freely and with the assurance that it will accurately register with the receptacle when closed so as substantially to cut off access of air to the receptacle.

A further object is to provide a simple and inexpensive device which occupies but little more room than the receptacle alone; which permits the receptacle to be closed and opened manually; which is dependable for its intended use, even if subjected to neglect or careless use; and which, after responding to a blaze, may quickly be restored to operative condition.

Other and further objects and advantages of the invention will be pointed out hereinafter in the following more detailed description and by reference to the accompanying drawings wherein

Fig. 1 is a perspective view of a support or holder for the receptacle including the receptacle cover and the means for holding the cover in nor-

mal open position, the cover being shown in the latter position;

Fig. 2 is a view similar to Fig. 1 but showing the receptacle in place;

Fig. 3 is a view similar to Fig. 2 but showing the cover closed;

Fig. 4 is a perspective view similar to Fig. 2 but looking toward the back or outer side of the open cover;

Fig. 5 is a fragmentary perspective view, to larger scale, showing details of the hinge construction; and

Fig. 6 is a fragmentary detail to large scale also showing details of the hinge and of the means for holding the cover open.

Referring to the drawings the invention comprises a base or support 1, here shown as of substantially U-shape in plane comprising a pair of more or less parallel arms 2 and 3 united by the curved or rear connecting portion 4. As illustrated, the arms 2 and 3 and the connecting portion 4 are integrally united and are made of angle stock so as to provide a horizontal flange and the upright flange 2^b. Preferably the forward ends of the arms flare outwardly so as to provide a broad base for the support. The closed end of the support constitutes a holder for a receptacle such as the pan R. Obviously if the support be designed for use with a pan or a receptacle of a different type, it may be shaped accordingly, but always with the purpose of furnishing a stable support or holder so that the pan or receptacle may not easily be overturned. While this support is here shown as made of angle stock, for example steel, it is contemplated that it may be made in other ways, for example as a casting, and that it may be made of other materials than metal if preferred.

Attached to the outer surface of the upright flange 2^b at the rear or curved portion 4 of the support is a rigid rod 5 for example of steel or the like, which is bent to a right angle at 7 and then extends upwardly to form the substantially vertical mast 8. The upper end of this mast may, if desired, be tapered and bent to form the forwardly projecting hook portion 9. Alternatively the hook may be made by securing a separate part to the otherwise straight mast.

At a point somewhat above the angle 7, preferably just above the level of the top of the pan, the mast is provided with a rigid loop member 10. This loop member, as here illustrated, consists of a piece of round stock of somewhat smaller diameter than the mast 8 and which is welded

at its upper and lower ends 11 and 12, respectively, to the material of the mast. This loop is disposed so that it lies in the vertical plane of symmetry of the support 1.

The cover 13 is preferably of metal and of a diameter such that when closed it completely covers the top of the receptacle R so as substantially to exclude air from the latter. In order to insure as tight a fit as possible, commensurate with simplicity and cheapness of construction, it is preferred to make the cover downwardly concave or at least to make its marginal portion concave so that it will contact the extreme edges of the pan or receptacle and tend to center itself upon the latter.

This cover is shown as a single piece of sheet metal and is provided near one margin with the hinge pin member 14 which, as here shown, is an integral part of the material of the cover. This pin 14 is located between an opening 15 through the cover and the inner end of a radial recess 16 leading inwardly from the edge of the cover. This hinge pin 14 is loosely embraced by the loop 10 and with the latter provides a hinge about which the cover may be swung up and down, but without any possibility of binding and with sufficient freedom so that the hinge elements are not likely to be fouled by the material within the pan. Preferably, in order to assure the proper registry of the cover with the pan as the cover moves to closed position, the cover is provided with rearwardly directed integral lugs 17 and 18 at opposite sides respectively of the recess 16 and which receive the mast 8 between them as the cover swings downwardly. By engagement of their inner edges with the mast, these ears 17 and 18 constrain the cover to move down accurately so as to register properly with the pan and thereby insure tight closure of the latter.

When the cover is in the fully open position it is not exactly vertical but inclines forwardly a little so that it tends, when released, to fall in response to the action of gravity and thus to cover the pan. In order to insure such positioning of the cover when fully open the mast is provided with a forwardly directed stop pin 19 and the cover is preferably furnished with a contact member 20 for engagement with this pin. If desired, this contact member may be adjustable, for example it may constitute the head of a bolt, so that normal position of the cover may be accurately determined.

At a point somewhat above the horizontal diameter of the cover when the latter is in upright position, there is arranged an eye 21 projecting from the inner surface of the cover and with its plane substantially horizontal. Two pins or posts 22 and 23 project from the inner surface of the cover, these pins being parallel and with their axes in a horizontal plane which is below the horizontal diameter of the cover. These pins are located at substantially equal distances at opposite sides of the vertical diameter of the cover and are of such length that their ends project outwardly and over the top of the pan R.

For holding the cover in normal upright open position there is provided a strand of organic material which is of a nature such that it easily deteriorates and loses strength when subjected to a substantial degree of heat. While strands of textile fiber or the like may be employed, it is preferred to use a rubber elastic strand, since in use this may be placed under substantial tension and thus, when its strength is locally reduced, it

tends, by reason of its own elasticity to contract and break even before the weight of the cover would accomplish this result, if it were not thus elastic. As here shown this strand comprises two loops 24 and 25 joined, for example, by a knot at the point 26. The loop 24 extends upwardly through the eye 21 and its upper end may be slipped over the hook 9 of the mast from which it may easily be released manually when desired. The other loop 25 is distended about the pins 22 and 23 and forms a tensioned, substantially horizontal run 27 between said pins and which overlies the pan R. When in use, loop 24 engages the hook 9 and the entire strand structure is under a certain degree of tension. During the normal operation of the device the cover remains in this position, held upright and open by the retaining strand. If the operator desires to close the cover it is merely necessary to release the loop 24 from the hook and allow the cover to drop. On the other hand, if while the pan is open, the contents of the pan should take fire, the rising flames immediately contact the transverse strand member 27 and cause it almost instantly to soften and break, thus permitting the cover to fall under the action of gravity and completely to close the pan and to cut off the supply of air and thus smother the blaze. After such an occurrence all that is necessary, in order to restore the apparatus to a condition of use, is to apply another cover-retaining strand which may be done almost instantly and by the user of the device and without the necessity of special tools or, in fact, of any implement other than the fingers.

The device thus provided is extremely simple and inexpensive but on the other hand it is effective for the desired purposes and may be depended upon to operate even though no especial care is taken to keep it clean or in proper condition. While one desirable embodiment of the invention has been here illustrated by way of example, it is to be understood that the invention is not necessarily limited to the precise arrangements herein described but is to be regarded as broadly inclusive of all equivalents and modifications which fall within the terms of the appended claims.

We claim:

1. In combination with a receptacle for inflammable fluid, a base constituting a support for the receptacle, a mast rising from the base, a cover for the receptacle, hinge means for the cover permitting the latter to move from a receptacle-closing position to an upright open position, and a thin strand of rubber elastic, easily deteriorated by heat, having one end attached to the upper part of the mast, the cover having a pair of transversely spaced posts projecting outwardly to a substantial distance from its inner surface, the opposite end portion of the strand having a loop therein which embraces the posts, the strand normally holding the cover in upright open position, the parts being so constructed and arranged that when the strand is holding the cover open that portion of the loop which extends between the posts forms a transverse tensioned run which is held away from the inner surface of the cover and in the direct path of flames rising from the receptacle.

2. In combination with a receptacle for inflammable fluid, a base constituting a support for the receptacle, a mast rising from the base, a cover for the receptacle, hinge means for the cover permitting the latter to move from a receptacle-closing position to an upright open position, a

thin strand of elastic rubber which normally holds the cover in upright open position, one end of the strand being attached to the upper part of the mast, a pan cover having a pair of spaced parallel posts projecting from its inner surface, the posts being disposed substantially symmetrically with respect to the vertical diameter of the cover, the strand having a loop in its free end portion which is spread to embrace both posts whereby a portion of said loop is held taut directly across the path of flame rising from the receptacle.

3. In a device of the class described, a substantially U-shaped base having spaced flaring arms designed to receive between them a receptacle for inflammable fluid, a mast rising substantially vertically from the closed end of the base, a receptacle cover provided with a hinge pin, the mast having a rigid hinge loop which loosely embraces said hinge pin, guide elements carried by the cover and disposed at opposite sides respectively of the mast thereby to insure registry of the cover with the receptacle when the cover moves to closed position, and a strand of material, easily disrupted by heat, normally extending between the mast and the cover and constructed and arranged normally to hold the cover in upright open position.

4. In a device of the class described, a substantially U-shaped base having spaced flaring arms designed to receive between them a receptacle for inflammable fluid, a mast rising substantially vertically from the closed end of the base, a receptacle cover provided with an integral portion near one margin constituting a hinge pin, a rigid loop member fixed to the mast and loosely embracing the hinge pin thereby permitting the

cover to swing up and down about the axis of said hinge pin, the cover having integral outwardly directed spaced ears disposed respectively at opposite sides of the mast and operative to insure registry of the cover with the receptacle as the cover swings down to closed position, and a thin strand of elastic material, easily disrupted by heat, normally extending between the mast and cover and constructed and arranged to hold the cover in upright open position, said strand normally being under tension.

5. In a device of the class described, a base shaped to provide a firm support for a receptacle for inflammable material, a rigid mast secured to the base and provided at its upper end with a hook, the mast also having a hinge loop projecting therefrom at a point spaced above the support, the plane of said loop being vertical, a cover having a hinge pin embraced by said loop, the cover also having a downwardly concave inner surface, a pair of spaced parallel posts projecting from the inner surface of the cover at opposite sides respectively of its vertical diameter and at that side of its horizontal diameter nearest the hinge pin, the cover also having an eye member projecting from its inner side near the upper end of its vertical diameter, and a thin strand of organic material which normally holds the cover in upright open position, said strand being arranged to form two loops, one of said loops extending through said eye member and engaging the mast hook and the other of said loops being spread to embrace the two posts whereby a portion of said latter loop is held taut and directly in the path of flame rising from the receptacle.
